UNITED STATES PATENT OFFICE.

KENNETH A. PALMER AND JOHN C. IRVIN, OF NEW YORK, N. Y.

MOLD.

1,307,872.

Specification of Letters Patent. Patented June 24, 1919.

Application filed July 6, 1918. Serial No. 248,667.

To all whom it may concern:

Be it known that we, KENNETH A. PALMER and JOHN C. IRVIN, citizens of the United States, residing at New York, county of New York, and State of New York, have invented certain new and useful Improvements in Molds, of which the following is a specification.

One object of our invention is to provide a mold which will be particularly adapted for use in vulcanizing the joined ends of rubber tubes, such for example as the inner tubes of automobile tires.

Another object of our invention is to provide a mold which will readily adapt itself to support a mandrel so that the latter can firmly hold the portion of the rubber tube, which is to be treated, in engagement with the steam-heated inner surface of the mold.

A further object is to construct such a mold in a manner which will permit the mandrel and the rubber tubes to be freely inserted and removed.

A still further object is to so construct our improved mold that a great efficiency will be secured from the steam which is inserted therein to cause the vulcanizing.

A further object is to provide our improved mold with means whereby a mandrel can be quickly and easily suspended and expanded therein.

These objects, and other advantageous ends which will be described hereinafter, we attain in the following manner, reference being had to the accompanying drawings in which—

Figure 1 is a top plan view of our improved mold showing a mandrel in the position which it occupies when ready for the vulcanizing process.

Fig. 2 is a section on the line 2—2 of Fig. 1 showing the mandrel in outside view and the tube, to be vulcanized, in dot-and-dash lines.

Fig. 3 is a view of similar nature to Fig. 1 showing how the mold appears without the mandrel or the rubber tube.

Fig. 4 is a fragmentary sectional elevation taken on the line 4—4 of Fig. 3 and drawn on a reduced scale.

Fig. 5 is a fragmentary section taken on the line 5—5 of Fig. 3, and

Fig. 6 is a fragmentary sectional plan taken on the line 6—6 of Fig. 2.

Referring to the drawings, 1 represents our improved mold which includes two sections 2 and 3 which are hinged together at

4. The section 2 is preferably held stationary, while the section 3 is permitted, when the mold is to be opened, to swing on 60 the hinge 4. Each of the sections 2 and 3 is substantially semi-circular in cross section, and interlapped joints 5 and 6 are provided so that the sections will neatly fit together. These interlapped joints 5 and 6 65 can be machined so as to form a neat fit and so that the inner surface 7 of each of the sections 2 and 3 will be flush.

The section 2 has two integral arms 8 which form a bearing or bracket for an 70 arcuate clamp arm 9 which is hinged or pivoted at 10. The end 11 of the clamp arm 9 has a conical extension 12 which is adapted to fit within a recess 13 in the side surface of the mold section 2. The opposite 75 end 14 of the clamp arm 9 supports a clamp screw 15 which can be operated by a handle 16 to firmly bind and hold the sections 2 and 3 together, as clearly shown in Fig. 1. The clamp screw 15 is adapted to engage a 80 recess 17 in the mold section 3 so that by the aid of the recesses 13 and 17 the clamp members can quickly find their centers and thereby render the clamping action easy.

The section 2 has a steam chamber 18 85 which extends substantially throughout its entire curvature, and the section 3 also has a steam chamber 19 which extends substantially throughout its curvature. Each of the steam chambers 18 and 19 has bottom 90 surfaces 20 which slant from the front toward the back for a purpose hereinafter to be described. Pet or drain cocks 21 are provided for the purpose of draining off the cold air from the steam chambers. 95

The section 2 is provided with a steam inlet passage 21^a and a steam pipe 22 is fitted therein, as clearly shown in Fig. 4. In similar manner, the steam chamber 19 of the section 3 has a steam inlet passage 23 which is provided with a nipple 24 so that a flexible hose or the like (not illustrated) can be attached thereto to admit the steam and permit the pivotal movement of the section 3 on the hinge 4. 100

The steam inlet passages 21^a and 23 enter the bottoms 20 of the respective steam chambers at their lowest points so that the water of condensation from steam will drain toward and into the steam inlet passages 21^a 110 and 23 so that the steam chambers will be kept free from water. Our improved mold, therefore, is self draining since the water of condensation drains into the steam inlet pas-

sages, and we therefore consider this a valuable and advantageous feature of our invention.

The upper end of the section 2 is provided with extensions 25 which have sockets 26 formed therein adapted to receive fingers 27 on a mandrel 28 so that in this manner the mandrel 28 can be suspended within the opening 29 of the mold, as clearly shown in Figs. 1 and 2. The mandrel 28 is of a type adapted to be slightly expanded by a downward movement of a wedge-shaped member 30, said member having a slot 31 formed therein. In other words, the mandrel 28 is made in sections 32 and 33 which are hinged together at 34 and by moving the member 30 downwardly the sections 32 and 33 are slightly expanded or increased in diameter and serve to tightly press the rubber tube 35 which is to be vulcanized and which surrounds the mandrel 28, against the inner surface 7 of the mold.

To move this member 30 to cause the expansion of the mandrel sections, we provide an operating lever 36 which is pivotally mounted at 37 to a bracket 38 on the top of the section 2 of the mold. The lever 36 has a pin 39 thereon adapted to engage the slot 31 in the member 30. The pivotal connection 37 for the lever 36 is such as to permit sufficient lateral movement of said lever to allow the pin to enter the slot 31 and to be freely removed therefrom. It is obvious that since the mandrel 28 is hung within the mold 1 through the engagement of the fingers 27 with the sockets 26 that a downward movement of the lever 36 will cause the member 30 to be moved downwardly and thereby expand the sections 32 and 33 as above set forth. The tube 35 to be vulcanized is so placed on the mandrel and within the mold that when steam is admitted into the chambers 18 and 19, the portion of the tube adjacent these chambers will be vulcanized and, as shown in the drawings, a seam 40 of the rubber tube is so positioned that the rubber immediately adjacent said seam will be vulcanized, thereby properly closing said seam and securing the ends of the tube together.

While we have described our invention as taking a particular form, it will be understood that the various parts of our invention may be changed without departing from the spirit thereof, and hence we do not limit ourselves to the precise construction set forth, but consider that we are at liberty to make such changes and alterations as fairly come within the scope of the appended claims.

Having thus described our invention, what we claim as new and desire to secure by Letters Patent is:

1. A mold of the character described hav-

ing an opening extending therethrough in a substantially vertical direction; an expandable mandrel adapted to be positioned within said opening; means for engagement with the top of said mold for suspending said mandrel in said opening; and mechanical means mounted independently of said mandrel and having a portion adapted to engage a part of said mandrel to effect the expansion of the latter within the mold, substantially as described. 65

2. A mold including two sections hinged together; a pivotally mounted double-ended clamp arm adapted to embrace said sections when together, said clamp arm being pivoted at a position to the rear of the pivot of said sections; and clamping means carried by 80 said arm for firmly holding said sections together, substantially as described. 75

3. A mold of the character described having an opening extending therethrough in a substantially vertical direction; an expandable mandrel adapted to be positioned within said opening; and means for engagement with the top of said mold for suspending said mandrel in said opening, substantially as 85 described. 90

4. A mold of the character described including sockets; an expandable mandrel adapted to be inserted within said mold and having portions for engagement with said sockets whereby the mandrel is suspended 95 within said mold; and mechanical means for expanding the mandrel when so suspended, substantially as described.

5. A mold of the character described including sockets; an expandable mandrel 100 adapted to be inserted within said mold and having portions for engagement with said sockets whereby the mandrel is suspended within said mold, said mandrel including means which, when moved, causes its 105 expansion; and mechanical means for moving said latter means to cause the expansion of said mandrel, substantially as described.

6. A mold of the character described including sockets; an expandable mandrel 110 adapted to be inserted within said mold and having portions for engagement with said sockets whereby the mandrel is suspended within said mold, said mandrel including means which, when moved, causes its 115 expansion; and a pivoted lever for moving said latter means to cause the expansion of said mandrel, substantially as described.

In testimony whereof we have signed our names to this specification in the presence of 120 two subscribing witnesses.

KENNETH A. PALMER.
JOHN C. IRVIN.
